HAIR CURLER

Lillian Lane Ryan, Brookline, Mass.

Application November 9, 1942, Serial No. 465,028

1 Claim. (Cl. 132—33)

This invention relates to hair waving or curling devices of the general type on which a strand of hair may be wound and the device then locked upon the strand.

Devices of this character have served their purpose in a fairly satisfactory manner but nevertheless have not been entirely satisfactory in some respects. For instance, when the hair is wound on the device, the initial coil often slips over the end of the device, or if not, it becomes loose and a non-uniform curl is formed. In many instances, after the hair is wound upon the device, the latter is bent and the ends hooked together or otherwise locked. This often results in discomfort for the user.

It is an object of the present invention to overcome such difficulties or at least reduce them to a minimum.

The invention will be more clearly understood from the following description in conjunction with the accompanying drawing: in which,

Fig. 1 is a perspective view of a device embodying the invention; and

Fig. 2 is a plan view of the device with a strand of hair wound thereon.

The hair curler embodying the invention as illustrated in the accompanying drawing comprises a narrow elongated strip of sheet material 10. The piece 10, preferably, is leather but other flexible sheet material may be used, such as fabric or even steel. The ends of the piece 10 may be rounded as indicated at 11. A series of recesses 15 are formed in one edge of the piece 10 and a series of recesses 16 are formed in the opposite edge. The recesses in one edge are nearer one end of the piece 10 than are the corresponding recesses in the opposite edge and thus form guides for winding a strand of hair in spiral form. In the preferred construction, as illus-

trated, the side walls 17 of the recesses 15 are aligned with the side walls 18 of the corresponding recesses 16. The strip 10 is provided with apertures 20 and 21 located near opposite ends thereof for a purpose described hereinafter. A V-shaped cut 22 in the strip 10 provides a longitudinally extending finger 23.

In using the device of the invention a strand 24 of hair is threaded through the aperture 20 and then is led directly into the nearest recess 16. The strand then is wound around the strip in spiral form by leading it from the first recess 16 to the corresponding recess 15 and then to the second recess 16 and so on until the strand has been wound in the last recess 15. From the last recess 15, the strand is passed or threaded through the aperture 21. The apertures 20 and 21 hold the windings in place as desired. During winding one or more convolutions of the strand 20 may pass under the finger 23 and the remaining convolutions over the finger, thus forming a wave in the hair.

I claim:

25 A hair curler comprising a narrow strip of sheet material having a plurality of recesses in each longitudinal edge, the recesses in one edge being nearer one end of said strip than the corresponding recesses in the opposite edge, said strip being cut to provide a longitudinally extending finger whereby a strand of hair may be wound on said strip in spiral form in said recesses with one or more convolutions passing under said finger and the remaining convolutions passing over said finger, said strip having an 30 aperture near at least one of its ends through which said strand may pass and thereby lock the curler in position.

LILLIAN LANE RYAN.
